Attorneys.

UNITED STATES PATENT OFFICE.

MILTON WITT, OF BUFFALO, NEW YORK.

VACUUM CLEANER.

Application filed July 12, 1926. Serial No. 121,768.

This invention relates to the type of vacuum cleaner having a brush arranged in the vacuum nozzle or chamber for disengaging the deeply embedded dust and dirt and cleaning lint and hairs from the nap of the rug or carpet without injuring it.

The object of the invention is to increase the nap-loosening action of the brush, in order to more fully utilize the cleaning action of the vacuum.

In the accompanying drawings: Figure 1 is a side elevation of a vacuum cleaner, partly in section, embodying the invention. Figure 2 is a bottom plan view thereof. Figure 3 is a transverse vertical section, on an enlarged scale, of the vacuum chamber containing the oscillatory brush.

Similar characters of reference indicate corresponding parts in the several views. 20 10 indicates the hollow body or frame of the machine supported by the usual wheels 11 and provided at its front end with a depending vacuum chamber 12 of any ordinary construction having the customary nozzle 13 which slides upon the rug, carpet or other object to be cleaned. The body contains any suitable vacuum creating device, such as a fan 14, shown by dotted lines in the drawings, the same being driven by an electric or other appropriate motor 15 also indicated by dotted lines. In the preferred form shown in the drawings, the fan is housed in a cylindrical enlargement 16 of the body, to the rear side of which is secured the usual hanger-bracket 35 17 which receives a handle 18 shown by dotted lines in Fig. 1.

Arranged in the vacuum or nozzle chamber 12 is a brush having a sweeping surface preferably consisting of tufts or bristles 19 projecting from the underside of the brush-stock or roller 20 which is journaled at its end in bearings formed in the end walls of the vacuum chamber. In the preferred arrangement of the bristles shown in the drawings, the same 45 are disposed in two parallel rows, the bristles in one row being staggered relatively to those of the companion row.

The brush is oscillated or otherwise moved back and forth during the use of the cleaner and it is so mounted in the vacuum chamber 50 that its bristles contact with the rug or other object to be cleaned both during the forward and backward strokes of the brush, so as to effectually loosen and separate the nap or rug-fibres and quickly and thoroughly disengage 55 the dirt from them as well as any clinging lint or hairs, thereby subjecting the same to the suction-action of the vacuum, fully utilizing its cleaning capacity and expediting the operation.

Any suitable mechanism may be employed for actuating the brush. For example, as shown in the drawings, it is oscillated by the electric motor 15 which drives the fan, through a worm gearing 22 including an upright rotary 60 shaft 23 journaled in the rear portion of the frame 10 and carrying a crank-member 24 which is connected by a link 25 with a rock arm 26 secured to the brush stock 20, whereby the rotary motion of said shaft imparts oscillatory motion to the brush. As shown in Figures 2 and 3, the rock arm is arranged centrally on the brush stock and operates in a compartment 27 formed in the nozzle 13, the rear wall of such compartment having an opening 70 28 for the passage of the link 25.

I claim as my invention:

In a vacuum cleaner, the combination of a frame having a vacuum chamber terminating in a nozzle, a compartment formed in the nozzle below and in communication with said vacuum chamber, said compartment having an opening in its rear wall, an oscillatory brush mounted on said frame and extending through said compartment, the brush having a rock 80 arm thereon operable in said compartment, and actuating mechanism for the brush including a rotary crank member and a link connecting the rock arm with the crank member, said parts being located exterior of the frame 85 and said link passing through said compartment-opening.

MILTON WITT.
